GUN PERFORATOR AND METHOD

Ira J. McCullough, Los Angeles, Calif.

Application May 19, 1936, Serial No. 80,548

28 Claims. (Cl. 164—0.5)

My invention relates to the art of perforating well casing, and relates particularly to a well casing perforating gun for use in perforating casing which has already been installed in the well.

5 In order that the features and advantages of my invention, as well as the objects thereof, may be readily understood, brief reference will be made to the oil producing industry in which my invention has broad application.

10 It is common practice to install in an oil well a well casing or oil string and to provide the portion of this well casing adjacent the oil bearing sands with perforations which allow oil to flow from the oil bearing sands into the well. There 15 are two methods of perforating the casing. One is to perforate the casing before it is installed in the well. The other method is to perforate the casing at desired elevations after it has been installed in the well. The method of perforating 20 the casing after it has been installed in the well may be used either on new wells which have not flowed oil or may be used on old wells where it is desired to place additional perforations in the casing or perforations at different elevations so 25 that oil sands which have not been previously utilized may be used.

It is an object of my invention to provide a device for perforating casing after it has been installed in a well in which projectiles or perforating elements are shot through the casing and into the formation.

It is another object of my invention to provide a perforator of the character mentioned in the preceding paragraph in which a plurality of projectiles or perforating means is simultaneously shot through the casing and into the oil sands in order that a heavy vibration will be set up which will cause vibration of the well casing, as well as the surrounding oil bearing formation, in order 40 to disturb the oil bearing formation and create or form channels through which oil may flow to the casing so that it may thereafter flow through the perforations thus formed in the casing and into the well.

45 It is a further object of my invention to provide a method and device for perforating a well after the casing has been installed in the well in which there is a plurality of projectiles, each of which is adapted to be propelled by the burning of a separate charge of powder, and in which the charges of powder are simultaneously lighted in order that all of the projectiles will be shot or projected from the apparatus at substantially the same time.

50 It is a further object of my invention to provide

a method and device of the character mentioned in the preceding paragraph in which all of the firing charges, that is, the charges of powder which propel the different projectiles, are substantially simultaneously lighted by means of an ignition flame which is formed within the perforating device.

5 It is a further object of my invention to provide a method of firing a gun perforator in which an ignition charge in a confined space is ignited to produce heated gases and build up pressure so as to ignite a firing charge in another confined space through a restricted passageway.

10 It is a further object of my invention to provide a fool-proof and safe mechanical actuating means whereby the powder may be ignited at the desired time.

15 It is a further object of my invention to provide an operating means in which the percussion means or the means which initiates the operation 20 of the apparatus is operated by means of a hammer which is dropped into the well from the surface of the ground, preferably around the cable, by means of which the perforating device is lowered into the well.

25 It is another object of my invention to provide a well perforating device of the character mentioned in which the percussion means has a disconnectable means so that the percussion means is inoperative except when the disconnectable 30 means is in a certain position. This is a safeguard against accidental or inadvertent operation.

It is a still further object of my invention to provide a perforating device of the character referred to heretofore in which the percussion 35 means has a retaining means associated with it which will not prevent intended operation of the apparatus, but will prevent accidental or inadvertent operation which might occur due to the well pressure or pressure of the fluid in the well. 40

It is a still further object of my invention to provide a relatively simple apparatus which is fool-proof in operation, which is sturdy in construction and will therefore withstand severe shocks and strains produced during the operation of the apparatus, and one which is easily cleaned and recharged for reoperation.

45 A further object of my invention is to provide a method and apparatus in which a pressure is first built up in the apparatus before the firing charge is ignited.

It is a further object of my invention to provide an explosive operated device, in which an ignition charge is burned in order to develop heat and pressure within the device, and which 50

55

is employed to ignite the explosive operating charge.

It is a further object of my invention to provide an explosive operated device, which includes a closed space or ignition chamber in which heat and pressure are first built up and which is in communication with the explosive operating charge chambers which contain explosive charges, and in which the heat and pressure or flame is transmitted through the ignition chamber to the explosive operating charges for igniting them.

It is a still further object of my invention to provide an explosive operated device, as pointed out in the preceding paragraph, in which the ignition chamber or closed space is connected to the different explosive charge chambers by restraining ports which are of relatively small diameter or area of cross section.

It is a still further object of my invention to provide an apparatus for perforating a well having the general features mentioned above and in which the priming means or igniting means is separated from the firing charge of powder, but is in communication therewith by a relatively small opening which permits the priming means or igniting means to ignite the firing charge of powder, but which prevents any material escape of powder.

Other objects and advantages of my invention will be made evident in the following description of the preferred form of my invention.

Referring to the drawings in detail:

Fig. 1 is an elevational view showing the utility of my invention.

Fig. 2 is a vertical sectional view showing the details of construction of the perforating device of my invention.

Fig. 3 is a sectional view taken on the line 3—3 of Fig. 2.

Fig. 4 is a sectional view taken on the line 4—4 of Fig. 2.

Fig. 5 is a sectional view taken on the line 5—5 of Fig. 4.

Fig. 6 is a sectional view taken on the line 6—6 of Fig. 2.

Fig. 7 is a sectional view taken on the line 7—7 of Fig. 2.

Fig. 8 is a sectional view taken on the line 8—8 of Fig. 2.

Fig. 9 is a sectional view illustrating a form of my invention in which but a single projectile is employed.

Referring to the drawings in detail, and particularly to Fig. 1, the numeral 11 represents the perforating device incorporating the features of my invention. It consists essentially of a cylindrical and elongated metal body which has connected to its upper end a flexible cable 12 which extends upwardly through the well casing 13 to the surface of the ground where it passes over a sheave 14 and is thereafter wound on a suitable drum 15. Associated with the sheave 14 is a measuring means 16 which includes a wheel 17 adapted for engagement with the cable 12, and which is connected to a meter 18 by means of a flexible cable 19. The purpose of the measuring means 16 is to indicate the depth of the perforating device 11 to enable this device to be lowered into the ground the desired number of feet, and when it reaches this position to be operated in order that the well casing 13 will be perforated at the desired level.

The general construction, as well as the details of construction, are shown in Figs. 2 to 8

inclusive. For the convenience of manufacture, the perforating device of my invention is made in a plurality of parts. However, I do not wish to be limited to the precise details of construction illustrated. The preferred form of my invention, as illustrated best in Fig. 2, includes a cylindrical and elongated body 25 which is preferably made from steel or from steel alloy which is capable of withstanding strains, shocks, and internal pressures. The upper end of the body 10 25 is provided with a threaded socket 26 so that a collar or connection member 27 may be secured thereto, this connection member 27 having a threaded pin 28 which is screwed into the threaded socket 26. The connection member 15 27 has a threaded pin 29 which is formed at the upper end of an upwardly projecting shaft 30. Connected to the threaded pin 29 is a cable socket 31, by means of which the cable 12 is connected to the apparatus. The lower end of 20 25 the cable 12 extends to the interior of the cable socket 31 and has the strands thereof separated, after which hot babbitt is poured into the place, thus providing an enlargement 32 which effectively secures these parts together.

Referring now to the details of construction provided by the preferred form of my invention, the body 25 includes a plurality of shooting means 33 which includes a powder chamber, a cylinder, and projectile, as will be now described with reference to Fig. 8. Formed in the body 25 are a plurality of openings 33 which are arranged at different elevations and which are alternately connected or joined to opposite sides of the body 25. Each opening 33 has a bottom portion which provides a firing-charge chamber or powder chamber 36, and adapted to be positioned in the firing-charge chamber 36 is a firing charge 37 which consists of a charge of powder enclosed in a suitable container 38 which may be made from cloth or paper. The outer portion of the opening 33 is provided in the form of a threaded portion 39 which is of larger diameter than the firing-charge chamber 36, thus providing an annular shoulder 40. Adapted to be screwed into the threaded portion 39 is a barrel or cylinder 41 which has an end face 42 which secures a gasket 43 against the shoulder 40, thus retaining the firing charge 37 in place and thus forming a gas-tight seal. In order to obtain the necessary strength to enable a building up of internal pressure and to withstand external pressure, as well as sealing qualities, this gasket is preferably made from a sheet of steel and a sheet of copper. The barrel or cylinder 41 is provided with a cylinder bore 44 which extends preferably at right angles to the longitudinal axis of the body 25 and is in communication with the exterior of the device at its outer end and in communication with the gasket 43 at its other end. The outer part of the cylinder or barrel 41 is provided with a polygonal portion 45 so that it may be installed or removed by the use of a suitable wrench. The cylinder 41 in the preferred form of my invention is a separate part so as to provide a convenient means for securing the gasket 43 in place and to permit convenient replacement when the bores become enlarged through use. My invention, however, is not limited to this particular arrangement, and the term "cylinder" as used herein and in the claims is to be construed as including cylinders which are either separate from or integral with the body. Likewise, the term "cylinder bore" or "bore" is to 75

be construed as covering any opening or passage in which a projectile is supported or through which the projectile is propelled. Placed in each of the cylinder bores 44 is a projectile 46 which is preferably provided with a pointed end 47. The projectile rests against the gasket 43, which has sufficient mechanical strength to withstand well pressures and keeps the projectile from being forced into the firing-charge chamber. For retaining the projectile 46 in place I prefer to use a body of grease 48 which fills the outer end of the bore 44, thus holding the projectile 46 against the gasket 43 and thus preventing the entrance of foreign matter or obstructions into the outer part of the bore.

This element of my invention is operated by igniting or lighting the charge of powder or firing charge 37, as will be described. This powder upon burning develops a high pressure in the firing-charge chamber 36 and ruptures the gasket 43 when the pressure builds up sufficiently. I find that more force may be applied to the projectile by making the gasket strong enough to cause a relatively high pressure to be built up before it ruptures the gasket and releases. This release of pressure applies a great force and fires the projectile 46 outwardly through the bore 44 with such force that the casing 18 will be easily penetrated and the projectile will be forced an appreciable distance into the surrounding formations.

The ignition means of my invention includes what I term an "ignition chamber", or space, or unobstructed passage 58 which is provided in the form of a cylindrical bore which is drilled into the body 25 preferably from the lower end thereof. The lower end of the ignition chamber 58 is closed by a removable plug 51, which plug may be removed after operation of the perforating device for the purpose of cleaning the ignition chamber 58. This plug 51 is, of course, provided with a suitable gasket 52 to form a gas-tight seal. The ignition chamber or space, or passage 58 is closed from communication with the exterior of the body 25. Connected to each of the firing-charge chambers 36 is an ignition port 53, which ignition ports are also connected to the ignition chamber 58 which extends in a vertical direction adjacent the different firing-charge chambers 36. The ends of the ignition ports 53 adjacent the firing-charge chambers 36 are reduced in size as shown at 54 for the purpose of diminishing the reduction of pressure by escape of gas through the ignition ports 53 after the firing charges 37 have been lighted.

The ignition means of my invention also includes a flame producing means which is provided by an ignition-charge chamber 56 which is provided by an opening 57 formed laterally into the body 25 from one side thereof as illustrated in Figs. 2 and 7. The ignition-charge chamber 56 is in communication with the upper end of the ignition chamber 58 and is adapted to contain an ignition charge 58 which is enclosed in a suitable container 59 which may be cloth or paper. This ignition charge 58, as will be seen from Figs. 2 and 7, projects slightly into the ignition chamber 58. The outer end of the opening 57 is provided in the form of an enlarged threaded portion 60 which threadedly receives a closure plug 61 which, when screwed in place by the application of the wrench 62, secures a gasket 63 against a shoulder 64 of the opening 57, thus forming a gas-tight seal.

Upon the lighting of the ignition charge 58,

as will be described presently, the burning of the powder produces a flame and considerable heat, and this flame is forced into the upper end of the ignition chamber 58 and almost instantaneously passes downwardly through the entire length of the ignition chamber. The flame or the intense heat of the flame, which is sufficient to cause an igniting of the firing charges 37, passes from the ignition chamber 58 through the ignition ports 53 and into contact with the firing charges 37, thus igniting or lighting them and causing an operation as pointed out heretofore.

The action of the ignition means of my invention is such as to produce a substantially simultaneous firing or lighting of all of the firing charges 37 so that all of the projectiles 46 are shot from the perforating device at substantially the same time. This is one of the important features of my invention, since it produces a very heavy explosion, and the projectiles substantially simultaneously striking the casing and entering the surrounding formation set up very heavy vibrations which are conducive to the providing of oil channels whereby oil may more freely flow to the casing for passage through the perforations of the casing into the well.

A further important feature is that the ignition charge 58 when ignited initially builds up a pressure in the apparatus so that when the firing charges are ignited there will not be a loss of power or pressure such as would be involved if it were necessary to employ the pressure of the firing charges to build up the pressure in the apparatus.

It will be seen from the foregoing discussion that the ignition chamber 58 and the ignition ports 53 provide a means for conveying the flame produced by the burning of the ignition charge 58 to or into contact with the various firing charges 37. It will further be seen that the ignition charge 58 constitutes a means for producing a flame or means for producing an igniting heat.

My invention also includes a means for lighting the ignition charge and this part of my invention includes a chamber 65 which is preferably formed in the body 25 from the upper end thereof and which is reduced in size at its lower end so as to provide an annular shoulder 66. Adapted to be placed in the chamber 65 against the shoulder 66 is a priming device which, for convenience, is in the form of a blank cartridge 67 which includes a percussion cap and a small priming charge which is ignited thereby. It will be seen that the lower end of the chamber 65 is in communication with the ignition chamber 58 so that when the priming charge burns it will in turn light the ignition charge 58. The cartridge 67 may be installed or removed from place through a breech opening 68 which communicates with the chamber 65 directly above the shoulder 66 and which is ordinarily closed by a plug 69 which secures a suitable gas-tight gasket 70 in place as shown. By removing the plug 69 and also the plug 61, which may be done after the device has been operated, a suitable device may be inserted upwardly through the lower end of the chamber 65 for forcing the cartridge 67 upward, and the cartridge 67 may then be removed through the breech opening 68.

As a part of the means for lighting the ignition charge my invention provides a percussion means. This percussion means includes a percussion rod 75 which extends downwardly into the chamber 65 above the cartridge 67 and has a percussion tip 76 formed on the lower end thereof. The

upper part of the percussion rod 75 extends through an opening 77 formed in the connection member 27. A seal is formed around the rod 75 by means of a stuffing box 78 which may be of any desired construction. The upper end of the percussion rod 75 extends into a horizontal slot 79 formed where the shaft 30 meets the main portion of the connecting means 27. The upper end of the percussion rod 75 has a small horizontal opening 80 for receiving a retaining means or shear pin 81, the extending ends of the shear pin 81 resting on the lower wall 82 which defines the bottom of the slot 79. The purpose of the retaining means 81 is to support the percussion rod 75 in the position shown in Fig. 2 and to hold it in that position so that any pressure within the well or the pressure of the fluid within the well will not, when applied to the upper end of the percussion rod 75, force it downwardly, as might occur were this precaution not taken. This would either result in an accidental firing of the perforating device or a destruction of the percussion cap so that it would not operate at the desired time. The percussion rod 75, being located wholly within the perforating device, may be referred to as an internal part of the percussion means.

Surrounding the shaft 30 and the socket 31 is a percussion sleeve 85 which, being located on the outside of the device, may be referred to as an external part. The upper end of the percussion sleeve 85 has an opening 86 through which the cable 12 extends, and the remaining part thereof has a relatively large cavity 87 within which the shaft and socket, parts 30 and 31, rest. For the purpose of preventing undue vibration or movement of the percussion sleeve 85 during the lowering of the device I provide a friction means which, as shown best in Fig. 4, is in the form of 40 diametrically opposed screws 89 carried by threaded openings 90 of the percussion sleeve 85 which have inner ends 91 which extend into vertically elongated slots 92 formed on the exterior of the shaft 30. By suitable adjustment of these screws 45 89 the desired friction may be obtained which will prevent rattling or movement, but which will not prevent proper operation of the percussion means.

The percussion means of my invention also includes a yoke or disconnectable means 93 which, as shown in Figs. 2 and 5, extends horizontally through the slot 79 and engages the upper end of the percussion rod 75. The ends 94 of the yoke 93 project outwardly from the shaft 30 and 55 are engaged by the lower end 95 of the percussion sleeve 85. Shoulders 96 are provided for preventing lateral movement and inadvertent removal of the yoke 93. This yoke 93 is removable by withdrawing the screws 89 and raising the percussion sleeve 85. When this is done the yoke 93 may be removed from place and the percussion sleeve 85 may be lowered so that the lower end thereof engages the upper end 96 of the large part of the connection member 27. It will be seen 60 that when this yoke 93 is removed there is no connection to the percussion rod 75 and the device cannot be operated. Furthermore, when the percussion sleeve 85 is in lowered position the slot 79 is fully closed so that it is impossible for 65 anything to get into the slot and inadvertently force the percussion rod 75 downwardly. Ordinarily I prefer to remove the yoke and lower the percussion sleeve whenever the apparatus is being transported and to properly position these 70 parts, as shown in Fig. 2, just before the perfora- 75

rating device is ready to be lowered into the well.

For the purpose of delivering a blow to the percussion means I provide a hammer 100 which, as shown best in Fig. 3, is preferably made in two parts 101 and 102 hinged at 103 and secured in closed position by means of a screw 104. This hammer 100 has an opening 105 through which the cable 12 extends when the hammer is positioned on the cable as shown in Figs. 1 and 2. The hammer is made of this type so that it need not be placed on the cable until the perforating device has reached the desired position and the operator is ready to fire the charges. He then places the hammer around the cable, secures it in place by proper manipulation of the screw 104, and then drops it into the well. The hammer follows the cable downwardly and strikes the upper end of the percussion sleeve 85. The force is transmitted through the percussion sleeve and the yoke and to the percussion rod 15. The force is sufficient to shear the retaining means or shear pin 81, thus permitting the percussion rod to be forced downwardly with a sufficient blow to fire the percussion cap and ignite the priming charge of the cartridge 67. 25

It is believed that from the foregoing the details of construction and the operation of my invention will be understood. A general description of its operation is as follows.

When it is necessary to perforate the well casing, such as indicated at 13, the perforating device is brought to the top of the well and connected to the cable 12 by the socket 31. At this time the charges and projectiles have already been properly placed in the apparatus and the only thing necessary for rendering the device operable is to raise the percussion sleeve 85, insert the yoke 93, and install the friction screws 89. This device is then lowered into the well by means of the cable 12, and when the device 40 has reached the depth at which the perforating operation is to be performed, this being indicated by the measuring means 16, the cable 12 is locked in a stationary position, and the operator then places the hammer 100 on the cable 12. 45 The hammer 100 is then released and it falls downwardly along the cable 12 and strikes the upper end of the percussion sleeve 85. This produces the sequence of operation described heretofore and consists of operating the percussion means which fires the priming charge. This in turn lights the ignition charge 58 which produces the flame which flows downwardly through the flame conveying space which includes the ignition chamber 50 and the ignition ports 53 building up an internal pressure as previously explained. This flame, passing into igniting or lighting contact with the firing charges 37, ignites the firing charges 37 and produces a gas pressure which when it builds 60 up sufficiently ruptures the gaskets 43 and shoots the projectiles 46 outwardly through the ports 44, thus piercing the well casing 13 and forming passages in the surrounding formation. 55

After the device has been thus discharged it 65 is raised to the surface of the ground, after which the device is cleaned, reloaded, and set for a subsequent operation. The cleaning is done by removing the plug 61 so that the ignition chamber 50 may be cleaned; by removing the plug 61 70 so that the ignition-charge chamber 56 may be cleaned; by disconnecting the connection member 27 to withdraw the percussion rod 75 so that the cartridge 67 may be withdrawn through the breech opening 68 after the removal of the plug 75

68; and by removing the various cylinders or barrels 41 so that the firing-charge chambers may be cleaned. A new blank cartridge 67 is then placed in the chamber 65 against the 5 shoulder 66 and new charges of powder are placed in the ignition-charge chamber 56 and the firing-charge chambers 36. New gaskets are installed in place of the gaskets 43 which have been ruptured, and new projectiles 46 and bodies 10 of grease 48 are installed in the barrels or cylinders 41. In addition to this a new shear pin 81 is installed in the opening 80. This places the device in condition for reuse and it is now ready to again be lowered into this well or some other 15 well for further operation.

In the form of my invention shown in Fig. 9 I employ but a single firing-charge chamber and projectile. This type of device is used for special 20 jobs, such for example as where it is necessary to perforate many strings of casing and layers of cement, in which case it is necessary to have a very heavy body and a very large charge of powder so that sufficient penetrating force can be obtained. In this alternative form of my invention all of the parts are the same except as 25 will be noted, and therefore the same numerals will be applied to this form of my invention as have been applied to corresponding parts of the form of my invention illustrated in Figs. 1 to 8 30 inclusive. In the form of my invention now being described the percussion cap and priming means 67 instead of being in communication with an ignition charge, as in the first form of my invention, of itself acts as the igniting means 35 or ignition charge. The device includes but a single powder chamber 38 and companion parts, as illustrated in Fig. 8, and is in communication with the priming means 67 by means of a relatively small communicating port 110 which, in 40 this form of my invention, constitutes the means for conveying the flame or igniting heat to the firing charge 37.

In view of the fact that the efficiency of the apparatus depends upon building up an extremely 45 high pressure in the powder chamber 38, I have separated the priming means 67 from the powder chamber 38. The communicating port 110 is so small that the loss of pressure through this small opening is negligible. It is, however, sufficiently 50 large to permit the priming means 67 to ignite the firing charge 37 whenever the percussion device is operating.

Although I have described herein the preferred 55 form of my invention, it should be understood that various changes and modifications may be made without departing from the spirit and scope of my invention as defined in the appended claims.

I claim as my invention:

60 1. In a device for perforating well casings in a well, the combination of: walls forming an ignition-charge chamber; an ignition charge in said chamber; walls forming a firing-charge chamber; a firing charge in said firing-charge chamber; a cylinder having a cylinder bore and positioned for communication with said firing-charge chamber; a projectile in said cylinder bore; lighting means for lighting said ignition charge for producing a flame; and walls forming 65 an unobstructed flame-conveying space, closed from communication with the exterior of said device, for conveying the flame to said firing-charge chamber for firing said firing charge.

2. In a device for perforating well casings in 75 a well, the combination of: walls forming an

ignition-charge chamber; an ignition charge in said chamber; walls forming a plurality of firing charge chambers; a firing charge in each of said firing charge chambers; a cylinder having a cylinder bore and positioned for communication 5 with said firing charge chambers; a projectile in said cylinder bore; lighting means for lighting said ignition charge for producing a flame; and walls forming an unobstructed flame-conveying space, closed from communication with the exterior 10 of said device, for conveying the flame to said firing charge chambers for firing said firing charge.

3. In a device for perforating well casing in a well, the combination of: walls forming an ignition-charge chamber adapted to receive an ignition charge; walls forming a plurality of firing-charge chambers; a plurality of cylinders each having a cylinder bore and each positioned for communication with one of said firing-charge 20 chambers; a projectile in each of said cylinder bores; lighting means for lighting the ignition charge for producing a flame; and walls forming an unobstructed flame-conveying space, closed from communication with the exterior of 25 said device, for conveying the flame to said firing-charge chambers for firing same.

4. In a device for perforating well casing in a well, the combination of: walls forming an ignition-charge chamber adapted to receive an ignition charge; walls forming a plurality of firing-charge chambers spaced from said ignition charge and each adapted to receive a firing charge; a plurality of cylinders each having a cylinder bore and each positioned for communication with one 35 of said firing-charge chambers; a projectile in each of said cylinder bores; lighting means for lighting the ignition charge for producing a flame; walls forming an unobstructed chamber into which the flame passes which is formed by the 40 burning of the ignition charge; and walls forming restraining ports connected to said unobstructed chamber and each of said firing-charge chambers.

5. In a device for perforating well casing in a well, the combination of: a plurality of cylinders having cylinder bores; a projectile in each of said cylinder bores; a firing charge adjacent each of said cylinders; an ignition charge; priming means for priming said ignition charge; percussion means for operating said priming means, said percussion means having an internal part, an external part, and disconnectable means normally operably connecting said parts together; a hammer for operating said percussion means; 55 and means in the form of an unobstructed passage closed from communication with the exterior of said device and in communication with said ignition charge and said firing charges.

6. If a device for perforating well casing in a well, the combination of: a plurality of cylinders having cylinder bores; a projectile in each of said cylinder bores; a firing charge adjacent each of said cylinders; an ignition charge; priming means for priming said ignition charge; percussion 65 means for operating said priming means, said percussion means having an internal part, an external part, disconnectable means normally operably connecting said parts together, and retaining means associated with said internal part for preventing inadvertent actuation; a hammer for operating said percussion means; and means in the form of an unobstructed passage closed 70 from communication with the exterior of said de- 75

vice and in communication with said ignition charge and said firing charges.

7. In a device for perforating well casing in a well, the combination of: a plurality of cylinders having cylinder bores; a projectile in each of said cylinder bores; a firing charge adjacent each of said cylinders; an ignition charge; priming means for priming said ignition charge; percussion means for operating said priming means, 10 said percussion means having an internal part, an external part, and disconnectable means normally operably connecting said parts together; a hammer adapted to be dropped into engagement with said external part for operating said percussion means; and means in the form of an unobstructed passage closed from communication with the exterior of said device and in communication with said ignition charge and said firing charges.

20 8. In a device for perforating well casing in a well, the combination of: a cylinder having a cylinder bore; a projectile in said cylinder bore; a firing charge adjacent said cylinder; an ignition charge remote from said firing charge; means 25 for igniting said ignition charge; and means in the form of an unobstructed passage closed from communication with the exterior of said device and in communication with said ignition charge and said firing charge.

20 9. In a device for perforating well casing in a well, the combination of: walls forming an ignition charge chamber, adapted to receive an ignition charge; walls forming a firing-charge chamber; a cylinder having a cylinder bore positioned for communication with said firing-charge chamber; a projectile in said cylinder bore; lighting means for igniting said ignition charge for producing a flame; walls forming an ignition chamber into which the flame passes which is 40 formed by the burning of said ignition charge; and walls forming a port connected to said ignition chamber and said firing-charge chamber.

10. In a device for perforating well casing in a well, the combination of: walls forming a firing-charge chamber adapted to receive a firing charge; a barrel having a cylinder bore positioned for communication with said firing-charge chamber; a projectile in said cylinder bore; walls forming a priming means chamber closed from communication with the exterior of said device; a priming means in said priming means chamber; means whereby said priming means is ignited; and walls forming a relatively small communicating and pressure restraining bore connected to said priming means and said firing-charge chamber.

11. In a device for perforating well casing in a well, the combination of: a cylinder having a cylinder bore; a projectile in said cylinder bore; a firing charge adjacent said cylinder; an ignition charge spaced from said firing charge; means for igniting said ignition charge; and walls forming an unobstructed space in communication with said firing charge and said ignition charge and substantially closed from communication with the exterior of said device so that when said ignition charge is burned heat and pressure are thereby developed in said space and transmitted to said firing charge for firing said firing charge and propelling said projectile.

70 12. In a device for perforating well casing in a well, the combination of: walls forming an ignition-charge chamber, adapted to receive an ignition charge; walls forming a firing-charge chamber; a cylinder having a cylinder bore posi-

tioned for communication with said firing-charge chamber; a projectile in said cylinder bore; lighting means for igniting said ignition charge for producing a flame; walls forming an unobstructed space in communication with said firing charge and said ignition charge and substantially closed from communication with the exterior of said device so that when said ignition charge is burned heat and pressure are thereby developed in said space; and walls forming a restraining 10 port connected to said ignition-charge chamber and to said firing-charge chamber whereby said heat and pressure are transmitted to said firing charge for firing the same and propelling said projectile.

15 13. In a device for perforating well casing in a well, the combination of: walls forming an ignition-charge chamber adapted to receive an ignition charge; walls forming a plurality of firing-charge chambers spaced from said ignition charge and each adapted to receive a firing charge; a plurality of cylinders each having a cylinder bore and each positioned for communication with one of said firing-charge chambers; a projectile in each of said cylinder bores; lighting means for igniting said ignition charge for burning same; walls forming a space substantially closed from the exterior of said device, and in communication with said ignition-charge chamber, so that when said ignition charge is burned 30 heat and pressure are thereby developed in said space; and walls forming a plurality of ports, each port being connected with one of said firing-charge chambers and said space and by means of which said heat reaches said firing charges and ignites them.

14. In a device for perforating well casing in a well, the combination of: walls forming a plurality of firing-charge chambers each adapted to receive a firing charge; a plurality of cylinders 40 each having a cylinder bore and each positioned for communication with one of said firing-charge chambers; a projectile in each of said cylinder bores; walls forming a space closed from the exterior of said device; an ignition charge in communication with said space and adapted to be burned to produce heat and pressure in said space; and walls forming a plurality of ports, each port being connected with one of said firing-charge chambers and said space and by means of which said heat reaches said firing charges and ignites them.

15. In a device for perforating well casing in a well, the combination of: walls forming a plurality of firing-charge chambers each adapted to receive a firing charge; a plurality of cylinders each having a cylinder bore and each positioned for communication with one of said firing-charge chambers; a projectile in each of said cylinder bores; walls forming a space closed from the exterior of said device; an ignition charge in communication with said space and adapted to be burned to produce heat and pressure in said space; and walls forming a plurality of relatively small restraining ports, each restraining port 65 being connected with one of said firing-charge chambers and said space, and constituting a means whereby said heat and pressure are first built up in said space and thereupon said heat passes through said restraining ports and ignites 70 said firing charges.

16. In a perforating gun of the character described, the combination of: a body providing a chamber to receive a priming means; percussion means for said priming means comprising a mov- 75

- able inner part, a movable outer part and a removable interconnecting part adapted when in place to connect said inner and outer parts; a shear pin engaging said inner part to hold the same in inoperative relation to said priming means; and operating means for imparting a force to said outer part, for transmission through said interconnecting part to said inner part, to cause shearing of said shear pin and actuation 10 of said priming means.
17. In a perforating gun of the character described, the combination of: a body having a chamber to receive a priming means in operative position; a percussion member supported so that it may be moved so as to actuate said priming means; a guard supported on said body so as to protect the outer end of said percussion member from inadvertent impact by an external object; and an insertable member adapted to be 15 placed in position to form a connection between said guard and said percussion member whereby force to move said percussion member may be transmitted thereto through the medium of said guard and said insertable member.
18. In a well perforating gun of the class described, the combination of: a body providing a cylinder bore having a projectile, a firing charge chamber adjacent said cylinder bore having a firing charge for propelling said projectile, an 20 ignition charge chamber spaced from said firing charge chamber having an ignition charge, and an ignition chamber closed from communication with the exterior of said body and in communication with said ignition charge chamber and 25 said firing charge chamber; and means for igniting said ignition charge.
19. In a well perforating gun of the class described, the combination of: a body providing a cylinder bore having a projectile, a firing charge 30 chamber adjacent said cylinder bore having a firing charge for propelling said projectile, an ignition charge chamber spaced from said firing charge chamber having an ignition charge, an ignition chamber closed from communication 35 with the exterior of said body and in communication with said ignition charge chamber, and a restraining port in communication with said ignition chamber and said firing charge chamber; and means for igniting said ignition charge.
20. In a well performing gun of the class described, the combination of: a body providing a plurality of cylinder bores each having a projectile, a plurality of firing charge chambers each positioned adjacent one of said cylinder bores 40 and each having a firing charge, an ignition charge chamber spaced from said firing charge chambers having an ignition charge, and an ignition chamber closed from communication with the exterior of said body and in communication 45 with said ignition charge chambers and said firing charge chambers; and means for igniting said ignition charge.
21. In a well perforating gun of the class described, the combination of: a body providing a plurality of cylinder bores each having a projectile, a plurality of firing charge chambers each positioned adjacent one of said cylinder bores and each having a firing charge, an ignition charge 50 chamber spaced from said firing charge chambers having an ignition charge, an ignition chamber closed from communication with the exterior of said body and in communication with said ignition charge chambers, and a plurality of restraining ports each being in communication 55 with said ignition chamber and one of said firing
- charge chambers; and means for igniting said ignition charge.
22. In a device adapted to be lowered into a well and operated therein by an explosive charge, the combination of: a body providing an explosive charge chamber for receiving said explosive charge therein, an ignition charge chamber spaced from said explosive charge for receiving an ignition charge therein, and an ignition chamber closed from communication with the exterior of said body and in communication with said ignition charge chamber and said explosive charge chamber, and means for igniting said ignition charge to cause said explosive charge to perform an operation in said well. 15
23. In a device adapted to be lowered into a well and operated therein by an explosive charge, the combination of: a body providing an explosive charge chamber for receiving said explosive charge therein, an ignition charge chamber spaced from said explosive charge for receiving an ignition charge therein, an ignition chamber closed from communication with the exterior of said body and in communication with said ignition charge chamber and said explosive charge chamber, and a restraining port in communication with said ignition chamber and said explosive charge chamber, and means for igniting said ignition charge to cause said explosive charge to perform an operation in said well. 20
24. In a device for perforating well casing in a well, the combination of: a body adapted to be lowered into the well, said body having a bore adapted to receive a projectile, and a powder chamber adapted to receive a charge of powder which when fired will propel said projectile from said bore; and percussion means for firing said charge of powder, including two parts operatively connected together by a removable member, which when removed renders said percussion 30 means inoperative.
25. In a device for perforating well casing in a well, the combination of: a body adapted to be lowered into the well, said body having a bore adapted to receive a projectile, and a powder chamber adapted to receive a charge of powder which when fired will propel said projectile from said bore; and percussion means for firing said charge of powder, including an inner percussion member supported within said body, an outer 35 percussion member supported on the exterior of said body and adapted to be struck by a hammer means, and a removable member operably connecting said percussion members together, said percussion means being rendered inoperative 45 when said removable member is removed.
26. In a well perforating device of the character described, the combination of: a body having a chamber adapted to receive a charge of powder, there being an opening extending upwardly from said chamber, the lower end of said opening being adapted to receive a priming means, and there being a port communicating with said opening at a point adjacent the position of said priming means therein and through which said priming means may be inserted or removed; means in said opening for setting off said priming means; and a removable closure member for said port. 50
27. The method of firing a projectile from a gun perforator for a well casing, which includes the steps of: confining an explosive charge in a chamber adjacent said projectile; confining another explosive charge in another chamber spaced from said first mentioned chamber; igniting said other explosive charge to produce heated gases 55

and build up pressure in said other chamber; and forcing said heated gases by said pressure through a restricted passageway between said chambers to ignite said first mentioned explosive charge and fire said projectile.

28. The method of simultaneously firing a plurality of projectiles from a gun perforator for a well casing, which includes the steps of: confining an explosive charge in each of a plurality of chambers; each of which is adjacent at least one of said projectiles; confining another explosive

charge in another chamber spaced from each of said first mentioned chambers; igniting said other explosive charge to produce heated gases and build up pressure in said other chamber; and forcing said heated gases by said pressure through restricted passageways between said other chamber and each of said plurality of chambers to simultaneously ignite said first mentioned charge and fire said projectiles.

IRAJ. McCULLOUGH.
